UNITED STATES PATENT OFFICE

ROYDEN EUGENE BEEBE, JR., OF BURLINGTON, VERMONT

LOOSE-LEAF BINDER

Application filed March 8, 1927. Serial No. 173,702.

The present invention relates to improvements in loose leaf binders and its particular object is to provide a loose leaf binder that is very simple in construction, can be made by the most simple means at the disposal of anybody and can be quickly improvised from materials usually at hand in any business or even in most households. It is proposed to utilize for this purpose an ordinary strap or band which is passed through registering perforations in a stack of sheets and which is provided with simple buckles or fasteners, which may be slid up against the stack from opposite sides for holding the sheets together. It is further proposed to provide in connection with this fastening means a simple cover made in such a manner as to hide the fastening means when applied, while the cover is secured to the stack by the fastening means. It is further proposed to arrange the cover in such a manner that the same may be readily improvised from practically any material at hand and particularly allows any ordinary book cover to be used. Further objects and advantages of my invention will appear as the specification proceeds.

The preferred form of my invention is illustrated in the accompanying drawing, in which

Figure 1 shows a perspective view of a stack of sheets held together by my fastening means;

Figure 2 a transverse section through the same;

Figure 3 a transverse section through a single arrangement having covers secured to opposite sides of the stack; and

Figure 4 a detail view of a strap or band used for hinging the leaves and covers together.

While I have shown only the preferred form of the invention, it should be understood that various changes or modifications may be made within the scope of the claims hereto attached without departing from the spirit of the invention.

In the form shown in Figures 1 and 2 a plurality of sheets 1, which may be single as shown in Figure 2, or double as shown in

Figure 1, are placed in stack formation and are formed with registering perforations 2 near one edge thereof, the perforations being preferably elongated to run parallel to the said edge so as to allow the straps or bands 3 to be passed therethrough. The straps may be provided at the ends with suitable stiffening members 4 facilitating the introduction of the same. The perforations 2 preferably communicate with slots 6 leading to the adjacent edge of the stack, the slots allowing the band 3 to be introduced from the edge, or allowing successive sheets to be introduced between the sheets originally used without necessitating a complete disassembling of the stack. The bands 3 have fasteners 7 slideable thereon.

The member 7 is shown as a clip formed with a pair of elongated slots 8 and a central rib 9. The band is guided through the slots. It will be seen from Figures 2 and 3 that the members 7 fulcrum on one of their edges and that force applied to move them on the bands will first swing the fulcrumed edge, and this will cause the opposite side to clamp the band 3 between it and the book. The greater the force exerted, the greater the clamping action. In this way accidental movement of the members is prevented. Instead of the fastener 7 I may use the well-known buckles 11, presenting points 12 adapted to penetrate into the material of the band at any place desired.

It will readily be seen that the construction shown in Figures 1 and 2 is of the simplest kind, merely requiring the assembling of the sheets in stacked relation, passing the bands through the registering perforations and causing the fasteners to bear on the stack from opposite sides thereof.

The form shown in Figure 3 adds the covers 13 comprising ordinary sheets of heavy material and having wings 14 hinged to one edge thereof, as shown at 16, the hinge preferably comprising a connecting piece of flexible material, leaving a certain amount of space between the wing and the sheet 13, when the former is folded upon the latter. The wings are provided with perforations 17 registering with those of the stack, and the band

3 is guided through the wings in the manner illustrated in Figure 3, the fastening means 7 being made to bear upon the wings from the outside, while the sheets 13, when folded upon the wings in the manner illustrated in Figure 3 completely hide the fastening means from view.

It should be understood that in the form shown in Figures 1 and 2 the outside sheets 10 of the stack may be made heavier to form covers. In this latter case the band may pass through the slots in the cover to partially conceal the same.

I claim:

15. 1. A loose leaf binder comprising a plurality of sheets having aligned perforations therein, a binding member extending through said aligned perforations, and an adjustable fastening member disposed on the binding member at each side of the sheets and being movable thereon for clamping the sheets therebetween, each fastening member being adapted to clamp the adjacent portion of the free end of the binding member to the sheets 20 when the sheets tend to separate at their bound edges.
20. 2. A loose leaf binder comprising a plurality of sheets having aligned perforations therein, a flexible binding member extending through said aligned perforations, and an adjustable fastening member disposed on the binding member at each side of the sheets, and being movable thereon for clamping the sheets therebetween, each fastening member 25 being adapted to clamp the adjacent portion of the free end of the binding member to the sheets when the sheets tend to separate at their bound edges.
25. 3. A loose leaf binder comprising a plurality of sheets having aligned perforations 30 therein, a flexible binding member extending through said aligned perforations, and an adjustable fastening member disposed on the binding member at each side of the sheets and being movable thereon for clamping the sheets therebetween, each fastening member 35 having one of its edges fulcrumed against the sheets, the opposite edges thereof normally being spaced from the sheets, whereby each 40 fastening member is adapted to clamp the adjacent portion of the free end of the binding member to the sheets when the sheets tend to separate at their bound edges.

ROYDEN E. BEEBE, JR.
